PROCESS FOR TREATING AND AGING FABRICS

Application filed June 18, 1930. Serial No. 462,047.

This invention relates generally to the treatment of fabrics composed of various materials, such as cotton, silk, rayon, wool or mixtures of said materials. Some fabrics such as celanese, require during aging, an atmosphere of steam that is less moist than others. Our improvements permit adapting an ager for efficient treatment of such fabrics as well as for those previously mentioned. 10 It is particularly applicable to the treatment of fabrics where an aging action through a reduction of the dyes is desired. It especially relates to the treatment of fabrics having thereon vat color prints or dyes and to discharge prints or other fabrics where the conversion of the dyes or chemicals used in printing or dyeing, into fixed patterns and uniform colors is necessary. The invention relates particularly to the process of 15 aging wherein a substantially closed chamber is supplied with an atmosphere of steam which excludes air and particularly oxygen so that the organic dyes are converted into the leuco bases. 20 Difficulties and objections which were almost universally encountered in aging vat color prints by the usual steam process, have been described and certain steps and apparatus for overcoming such difficulties and 25 objections have been set forth and claimed in the prior patents to R. W. Jacoby, No. 1,663,845 and No. 1,663,846, issued March 27, 1928. 30 Generally speaking, the present invention 35 comprises supplying a correct amount of moist steam or vapor at points adjacent the runs of fabric in an ager where the excess heat is actively generated. 40 The moisture content of such steam or vapor is also controllable to a nice degree either by the introduction of water into the steam which is supplied between the runs of the fabric or by adding water to the steam as it escapes into the spaces between said runs 45 or by both. 50 Incident to this supply of moist vapors at the points where the generation of excess heat is greater than elsewhere, is the circulation necessary to be produced in order to remove the vapors which have to a greater or less extent absorbed the excess heat generated. In the prior patents of E. S. Chapin and A. H. Jacoby No. 1,738,946 and No. 1,738,947 issued December 10, 1929, certain devices and means are described for producing a greater circulation of the vapors at such points. 55 These improvements are all of value in connection with the present inventions as are also aprons that are similar in function to those described and claimed in Patents No. 1,663,845 and No. 1,663,846 above mentioned. That is to say, the use of the present aprons enables the water and moist steam vapors to be employed and evenly distributed within the ager without the disadvantage of spotting the prints or fabric. 60 Patents No. 1,738,946 and No. 1,738,947 describe in detail various steps and devices which have been found to be very great advances in the art of aging fabrics and set forth as far as was then possible the causes of certain rises in temperature due to the generation of excess heat which occurs during the aging process. Said patents also describe and claim improvements which have been found to provide definite and valuable advances over the prior art and practices. 65 This application is a continuation in part of our prior application, Serial No. 359,156, filed April 29, 1929, for apparatus for treating and aging fabrics, and some of the present process claims were divided out of said prior application in accordance with the requirement therefor. 70 In the usual process of aging, the aging chamber is supplied with an atmosphere of steam which excludes air and particularly oxygen so that the organic dyes are reduced to the leuco bases. This treatment with steam constitutes what is known as the aging and during the aging process considerable heat is produced by various chemical and physical actions and reactions occurring within the ager. The leuco bases are water soluble and therefore can be absorbed by the fibers of the fabric. After the aging process is completed, the dyes are fixed in the fibres of the fabric by oxidation through incidental contact with the oxygen of the air and by 75 80 85 90 95 100

treatment with water solutions of soap, etc. This oxidation causes the dyes again to become insoluble and results in exceedingly fast colors.

5 In the use of the usual aging apparatus, it has been found impossible to maintain the temperature at desired points throughout the ager to carry out the aging process entirely satisfactorily because the sources of liberation of heat have not been definitely known and consequently no positive remedy has been provided.

We have found that the causes of the rise in temperature are due to various conditions 15 resulting from the actions and reactions which occur during the aging process. These include the giving off of latent heat contained in the water vapors when they are condensed upon the fabric as it passes through 20 the apparatus, chemical reactions resulting from the reduction of the dyes, heating coils intended to maintain the desired temperature, steam chests used to prevent condensation, and the heating of the rolls and other 25 metallic parts which tend to absorb and then radiate heat.

The present application involves improvements in the process and apparatus for aging fabrics whereby the temperatures and the degrees of moisture required at various points within an aging chamber are most accurately controlled so that a control permits with greater efficiency the aging of a great variety of fabrics and a great variety of different 30 designs which require the various kinds and quantities of dyes. In fact the control has been carried to such an extent by the improvements to be set forth in the present application that temperature time cards taken 35 at various points in an ager show that the temperature can be maintained at all points in the ager while the aging is taking place so as to be very uniform throughout the entire day and such temperatures may be controlled accurately and at will within one or 40 two degrees of the most efficient temperature required for the particular goods and dyes being treated.

The aprons described and illustrated in 45 Patents Nos. 1,663,845 and 1,663,846 enabled water to be introduced between the runs of the the fabric at points where the generation of objectionable high temperatures have occurred, and enabled the steam which had 50 become superheated by the reactions of the dyes and the fabric, to absorb moisture and thereby increase the moisture content of the steam. This principle is availed of in the present improvements but certain additions 55 have been made which increase the efficiency of the aprons and permit greater control of the temperature and of the moisture content.

60 It will be realized that when steam is to any considerable extent superheated it tends to rise in accordance with well known physi-

cal laws. This causes the superheated steam to accumulate between the runs of fabric beneath the rolls and in the upper portion of the ager.

Owing to the close proximity of adjacent 70 runs of fabric passing about rolls in the lower portion of an ager, circulation is inadequate and pockets are formed from which the heat generated does not ordinarily rise and is therefore not dissipated or removed 75 without the use of the special arrangements of our apparatus.

It is therefore one object of the present invention to supply not only water, but so to preserve the moisture content of the steam 80 at such points that the temperature will not be raised to an undesirable degree and also may be controlled at will to produce the most efficient aging action at various points within the ager, depending upon the local conditions 85 which may exist therein.

The giving-off of heat varies to a large extent according to whether the fabric is heavy or light, whether one or more strings are run or whether the pattern requires 90 greater or less quantities of dyes, that is, it varies with the weight of the fabric and with the coverage and depth of the color of the pattern. The heat-producing reaction due to the fabric itself takes place independently 95 of the dyes and is an important factor in the treatment of fabrics passing through an ager. This reaction takes place during the conversion of the dyes into their leuco bases.

These conditions establish the necessity of accurate control of the character of the steam forming the vapor in which the aging takes place. The character of this steam involves several factors which must be considered to produce an aging action in the most efficient 100 manner. These factors may be enumerated as follows:

- (a) The quantity of the steam;
- (b) The temperature of the steam;
- (c) The amount of moisture carried by 110 the steam;
- (d) The points at which the steam is applied to the fabric; and
- (e) The time during which the steam is allowed to act upon the fabric.

The subject matter of this application relates to all of these factors, and especially to the factors (c) and (d) concerning the amount of moisture carried by the steam, at points where excess heat is generated, whereby the heat is neutralized, absorbed and dissipated to produce proper conversion or reduction at such points.

The last time element (e) is also an important factor in aging. Generally up to a 115 certain period of time the color value of the dyes is increased, while for shorter or longer time the color value is lessened. This consideration obviously involves the question of maximum production for one or more aging 120

units and a determination of the maximum speed of the fabric through the ager consistent with high color value and minimum cost for dyes.

- 5 In most instances of the treatment of vat color prints the original organic dyes are made into a paste form by mixing with them hydrosulphite of soda, caustic soda and a thickening material, such as starch, dextrine, 10 gum arabic, etc. After the fabric is printed by suitable engraved copper rolls or otherwise, it is dried and passed into the chamber known as an ager comprising rolls over which the fabric passes in successive vertical runs. 15 Ordinarily, when the goods were finally washed after aging, the operation was usually accompanied, in different degrees, by the washing away of a considerable quantity of the dyestuff which had not become fixed in or 20 on the fabric. This was true in some instances to the extent that practically 50% of the dyestuff was lost through inefficient reduction and oxidation. The dyestuffs used in the printing of fabrics are, as is well 25 known, comparatively expensive organic materials and the reduction in the cost thereof is an important factor in the total cost of treating the goods, and, naturally, when accomplished, ultimately permits a greater return on the price per yard of the finished 30 product. One of the important results of our process is therefore a more complete and efficient use of dyestuffs because in the final washing very little, if any, of the original 35 dyeing material is wasted.

As will be appreciated by those familiar with the art of aging fabrics, the aging process is carried out upon a great variety of goods, particularly as to the weight of the 40 fabric and the amount of the dye applied thereto. The heavier fabrics having the coloring dyes applied thereto in considerable quantity or in relatively heavy coatings, naturally develop considerably more heat in the 45 aging process than do lighter fabrics having lighter coatings of the dyeing material applied thereto.

Furthermore, different coloring matters in materials produce different amounts of 50 heat which are generated during the aging process. It thus becomes necessary in the aging of various fabrics to control the action of the heat generated so that it will not become so high as to interfere with the subsequent actions as the process proceeds.

Not only should the heat generated be removed from the vicinity of the fabric as rapidly as possible, but the steam subsequently supplied to act further upon the dyes and 60 the fabric to continue the reactions should be so provided as to quantity and quality that the conditions within the ager may at all points be maintained under the best conditions to produce the desired result.

65 One of the objects of the present invention

is, therefore, to produce an improved process by means of which the fabric being aged may be treated uniformly and efficiently without involving the usual disadvantages heretofore experienced resulting from the presence of an undesirable amount of heat or too great or too small an amount of moisture. We have found in most instances that when steam is supplied to the aging apparatus through the usual means, such as taking directly from a boiler or other steam generator used for driving a steam engine or turbine, the reduction of the pressure by reducing valves before entering the ager causes the steam to enter the ager in too dry a condition, 75 and its quantity and quality are not such as are suitable to give uniform and efficient results because of the superheated condition of the steam.

This is also true of steam which has been taken from a boiler such as above mentioned and allowed to expand in an expansion chamber, although owing to the radiation from such an expansion chamber, the amount of moisture contained in the steam may be greater than that when direct steam is used. This method, in certain instances, has, however, been found to produce better results in the ager than the use of steam direct from a 85 boiler.

A third source of steam is the exhaust from a steam power generator, such as a steam turbine. In this case, some of the heat has been extracted from the steam by reason of the power developed in the generator or turbine; therefore, for a given amount of steam, the 95 pressure is somewhat lower and the steam more moist.

It is clear, however, that the steam which is introduced into the ager at various points must be of the right quantity as well as of the right quality as regards temperature and degree of moisture to produce the best effects in any particular ager, depending upon the kind of goods being treated or the amount of 105 dye materials thereon.

As a result of our researches and experiments, we have found that the steam when passed through an ager in comparatively 115 larger quantities than generally used from a source having a low pressure is best adapted to produce the desired results.

This is particularly true if the action of the steam be permitted to continue for a considerable time beyond that usually considered necessary under the conditions formerly existing.

The quantity of such steam has been determined by flow meters, and by the use of such meters it has been found that at least 125 1800-2000 lbs. of such steam per hour preferably should be used.

As far as we are at present advised, no apparatus has yet been devised to determine through any other form of indicator the 130

amount of moisture which may be present in steam after it has been introduced into an aging apparatus and the best available indicator for the conditions of the heat existing within the aging apparatus is the thermometer, these thermometers being placed at various places so as to indicate the temperatures at various points. We have found contrary to the usual practice, that it is necessary and essential so to locate thermometers that the temperatures between the runs of the fabric at various points within the apparatus may be accurately determined, particularly in the central longitudinal zone where the highest temperatures usually occur. We have found that when the quantity and quality of the steam have been correctly adjusted by controlling the supply, the temperature within the ager at such points ordinarily should be about 215°, although in some cases, depending upon the nature of the fabric and the printing, it may be somewhat higher or lower than those temperatures.

We have also found that the initial reactions at the forward end of the aging apparatus produce the greater amount of heat, and, therefore, especial attention is necessary to prevent abnormal rising in temperature at that part of the aging apparatus. It is therefore particularly desirable to produce a somewhat more rapid circulation of the vapors at certain points and then to remove or exhaust them so that vapor containing the excess heat developed may be rapidly displaced and its place taken by more moist vapors, as set forth in our prior patents above mentioned.

In the general commercial use of former agers, as employed in the cloth printing industry, it has been found that the depth of the color produced varies to a considerable extent. Thus when the ager was first started, the resultant color was considerably deeper than that secured after the ager had been run for several hours. Not only this, but in the course of a day's run the color value would go off and this might even occur during the course of a single run.

The definite cause of such conditions was practically unknown prior to our researches and the result was that at times a considerable percentage of the finished goods had to be discarded or sold as an inferior product or "seconds".

Through the use of our improved process and apparatus the certainty in the color value of the printed fabric produced has been greatly increased and we have been enabled to produce a fabric in which any defects that may occur do not result from the treatment during aging, but are due to other conditions which may have existed during the actual printing or during other treatments not connected with the aging process or apparatus.

Owing to this fact, which results from the

definite condition of the quantity and quality of the steam which is present within the ager, we have been able to produce great regularity in the process.

Furthermore, the product is practically uniform and of greater depth of color per unit of dye or other coloring substance than has heretofore been possible to obtain.

In addition to these results as to uniformity and depth of color, and the reduction in the amount of defective goods, we have been able to accomplish another result which is of great importance in the practical industry of printing and producing vat color prints—that is, the reduction in the quantity of dyestuffs employed.

Some of the advantages above stated may be accomplished by the use of our inventions without any substantial increase in the time required for treating the fabrics, as we have found that material may be aged, if desired, in substantially the same time as required in the old or previous aging apparatus, and with greatly improved results.

The following description taken in connection with the accompanying drawings sets forth a preferred form of process and apparatus in which the present improvements are embodied and involve certain improvements over the devices and processes of said prior patents.

Referring to the drawings, Fig. 1 is a longitudinal sectional view of an improved ager constructed substantially in accordance with the present invention;

Fig. 2 is a plan view thereof, showing more especially the pipe connections;

Fig. 3 is a cross-sectional view taken substantially on the line 3—3 of Fig. 1;

Fig. 4 is a cross-sectional view of one of the aprons indicated in Fig. 3, showing the relative positions of the water and steam pipes;

Fig. 5 is a cross-sectional view of a portion of the device as shown in Fig. 3 on an enlarged scale, showing the details of the water and steam supply pipes;

Fig. 6 is an elevation of the right hand lower portion of the ager as shown in Fig. 3, and indicating the pipe connections;

Fig. 7 is a partial view of the screen located in the lower portion of the ager, and

Fig. 8 is an enlarged view of the piping connections adjacent the mixing chamber.

Referring to the drawings the numeral 1 indicates a casing of sheet material, which forms the body of the ager, and which is covered with a suitable heat insulating material 2, to prevent the escape of heat. At the upper left-hand side of the ager is an opening 3 through which the cloth may enter and emerge from the interior of the ager. The opening 3 is provided with means to suck away the steam which would tend to be discharged through said opening, said means

preferably comprising a fan or other form of suction device 4, having a pipe 5 leading from the interior of horizontal hood 6, adjacent the opening 3 through which the cloth passes in entering and emerging from the ager.

The top portion of the ager is provided with a plurality of hollow heating plates 7, which are provided with steam, as hereinabove described, so as to maintain the inner top surface or ceiling of the ager at such a temperature as to prevent the condensation of moisture from the steam in the ager, thereby preventing drops of water falling on the fabric being treated.

The interior of the ager is provided with two series of rolls 8 and 8', over which the cloth to be aged passes successively in substantially parallel runs, after entering through the opening 3, as indicated in Fig. 1.

Rolls 9 are provided to support the fabric as it returns toward said opening 3.

A wire mesh or similar screen 10, having substantially the same length and width as the interior of the ager, is positioned below the lower series of rolls 8', so as to prevent the goods being treated in the ager from being spattered by drops produced in the interior of the ager by the inflowing steam.

The screen 10 also serves to distribute the inflowing steam throughout the ager.

The bottom of the ager is provided with a plurality of drain pipes 11, through which the water of condensation in the ager, etc. may be discharged.

The arrangement of piping for supplying steam under the proper conditions of temperature, pressure and moisture content will now be described. In the drawings the numeral 12 indicates the main steam supply pipe through which steam from a suitable source of supply flows. The pipes 14 and 15 are connected to the supply pipe 12 and has associated with them a suitable valve 13 to control the admission of steam to the aging apparatus. The pipe 12 communicates with a pipe 14 (see Fig. 2) which in turn connects with a vertical pipe 15 shown more clearly in Fig. 1. From the vertical pipe 15 two horizontal branch pipes 16 and 17 extend as shown in Fig. 2. The pipe 16 has connected thereto the valves 18 and 19 which are adapted to stop the flow of steam therethrough. An automatic regulating valve 20 is also provided in the pipe 16 to reduce the pressure of the steam flowing through the pipe 16 to any desirable pressure below the pressure of the steam supply from the main pipe 12. And this valve is made inoperative by the valves 18 and 19. The pipe 17 is connected to pipe 16 beyond the valve 19, thus constituting a by-pass. A valve 21 is inserted in the pipe 17 and it will be readily understood that by closing the valves 18 or 19 in the pipe 16 and opening the valve 21 in the pipe 17,

the steam may be caused to flow through the by-pass 17 instead of flowing through the pipe 16 and regulating valve 20, thereby permitting repair or adjustment of the latter.

The opposite end of the pipe 16 is connected to a riser 22 which in turn communicates with a horizontal pipe 23 connected to a mixing chamber 24, as clearly illustrated in Fig. 2. Referring now to Fig. 8 it will be seen that the pipe 23 is provided with a T 25 having a reducing plug 26 screwed into one opening. Water is supplied to the interior of the mixing chamber 24 through the pipe 27 which is connected to the T 25 through the reducing plug 26, as shown more clearly in Fig. 8. A valve 28 in the pipe line 27 controls the admission of water to the mixing chamber 24.

In the mixing chamber 24 the steam flowing through the pipe 23 and the water flowing through the pipe 27 are caused to be thoroughly mixed, and by proper manipulation of the steam and water control valves described above, steam of proper pressure, temperature and water content can be prepared for use in the ager as specified above in this specification. The mixing chamber 24 is provided with a suitable safety valve 29 to prevent the pressure of the steam chamber 24 rising beyond safe limits.

From the mixing chamber 24 the steam flows through an outlet pipe 30 which communicates with the branch pipes 31 extending across the width of the ager and slightly beyond. The branch pipes 31 communicate with vertical pipes 32 which are connected at their lower ends with the steam manifolds 33 extending along the length of the lower portion of the ager as shown in Fig. 3. From the manifolds 33 the steam flows through pipes 34 which extend into the ager and are perforated as shown. The arrangement of the perforated pipes 34 is clearly indicated in Fig. 2. It will be observed from Fig. 1 that the screen 10, being positioned between the perforated pipes 34 and the lower series of rolls 8' prevents water spattering on the goods being treated. Pipes 33 are provided with valves 35 for controlling the supply of steam to the manifolds 33.

Steam is supplied to the steam plates 7 located at the top of the ager through the pipe 36 which connects with a horizontal manifold 37 extending along one side of the ager as shown in Fig. 3. From the manifold 37 pipes 38 convey steam to the interior of the steam plates. The drains 39 communicate with the interior of the steam plates 7 and lead into a horizontal manifold 40 through which the exhaust steam and moisture from the steam plates flow.

A temperature recording device 41 may be associated with the outlet pipe 30 from the mixing chamber 24 so that a permanent record of the temperature of the steam supplied

to the ager may be kept. Flow meters and other devices measuring the quantity, pressure and temperature of the steam may be located in desirable portions of the piping system so that an accurate record of the quantity and quality of the steam supplied to the ager may be recorded.

As indicated by the use of the above described apparatus, one feature of our invention ¹⁰ comprises a correct selection and control of the source of steam as to quantity and quality, particularly as regards temperature and moisture in the main portion of the ager. This is usually accomplished by the use of ¹⁵ steam which is comparatively wet, that is, steam from which some of the normal heat content has been abstracted either by radiation, or by adding water to steam whose pressure has been reduced, as above described, ²⁰ or by other similar means.

Further improvements in the process and apparatus for aging will now be described.

Referring again to Fig. 1 of the drawings, it will be seen that the first three pairs of the ²⁵ upper rolls 8 and two pairs of the lower rolls 8' are separated so as to provide wider spaces between the runs of the fabric, than are provided between the subsequent rolls toward the right-hand end of the ager. This separation of the rolls results in two advantages. In the first place, the spaces above the horizontal runs of the fabric which pass between the lower rolls allow a rapid circulation of ³⁰ the steam vapors in the spaces between the upper rolls so that they may be easily withdrawn by the suction of the fan; and secondly, the space below the runs passing between the upper rolls allows the introduction of aprons which have been referred to above.

³⁵ These aprons are preferably constructed in the following manner. Referring to Figs. 3, 4, and 5, it will be seen that there is a rectangular casing 43, preferably made of wire-mesh screen material such as copper, brass or other suitable metal. This is supported on suitable metallic frames 44, and is closed at the ends and top. A pipe 45 passes through the upper portion of this casing, which pipe is preferably slotted at its upper side as indicated at 46. This pipe is supplied with water from the main water supply pipe 47, and in the pipe connections are valves 48 for controlling the flow of water.

⁴⁰ The pipe 45 has suitable supports 49 on the walls of the casing 1, and since the said pipe passes through holes in the casing 43, the casing is thereby supported in a vertical position. Collars 50 are placed upon the pipe 45 to prevent the casing 43 from sliding longitudinally thereon and are preferably attached to said casing by soldering or otherwise. The casing 43 is preferably composed of 3 or 4 ⁴⁵ layers of wire mesh so as to more effectively equalize and distribute the flow of moist va-

pors therethrough, as will hereinafter be more fully described.

The left hand manifold 33 (Fig. 3) has a series of nipples which connect with valves ⁷⁰ 51 and the latter are connected with the pipe connections 52. One outlet of these T connections carry pipes 53, which connect with vertical pipes 54. These pipe connections and the valves are preferably of the 2-inch size. The other outlets of the T connections ⁷⁵ 52, carry pipes 55, having valves 56 which connect with a live or high-pressure steam manifold 57, the purpose of which will be more fully described hereafter.

The upper portion of the pipes 54 carry ⁸⁰ three more or less, horizontal branches 58, 59 and 60, the ends of which are closed as indicated in Figs. 3 and 5, and each of which are provided with series of perforations or holes, through which the steam may escape. These ⁸⁵ holes are preferably more numerous in the upper branches 60, less numerous in the branches 59 and still less numerous in the branches 58. These pipes, as indicated in Figs. 1 and 4, are located between the two ⁹⁰ sides of the wire mesh apron or casing 43, and are preferably all adjacent to or above the center of the casing and directly beneath the pipe 45. The valves 51 are provided for the purpose of controlling the flow of steam to ⁹⁵ the pipes 53, and the branches 58, 59 and 60 connected herewith.

It should be noted that there are three sets of casings 43, and each has a corresponding steam supply pipe located between the ¹⁰⁰ sides thereof and a water pipe 45 located at the top thereof. Obviously, the number of these pipes and casings may be varied according to the requirements of a particular ager designed for a particular or special use. ¹⁰⁵ In an ager in which three or more aprons are provided, any number of them may be placed in operation or may be made inactive as desired according to whether or not the steam and water are admitted thereto.

The operation of this portion of the ager will now be described:

Assuming that the ager has been started, and the material atmosphere thereof generally provided with the necessary amount of ¹¹⁵ steam vapor through the steam supply pipes at the bottom of the ager, the passage of the fabric through the opening 3 and over the rolls 8 and 8', as indicated in Fig. 1, will cause the conversion of the dyes to start immediately, upon coming in contact with the warm moist vapors of the ager. This conversion, owing to the physical and chemical reactions, which take place within the ager, produces a considerable amount of excess heat, as has been explained in the prior patents above mentioned. This production of excess heat occurs at times with almost explosive force in the forward part of the ager soon after the cloth enters the same, and at this point, ¹²⁰ 125 130

the neutralization, absorption and dissipation of the heat is required to a greater extent. This is the reason that the special means in the form of aprons and wider spaces between the runs above described have been provided. The flow of water through the pipes 47 and 45 allows the water to escape through the slot 46 at the top of the pipe 45, and it accordingly runs or trickles downward over the sides 10 of the pipe in a greater or less volume, according to the adjustment of the valve 48. The steam pipes 33, 53, 54, 58, 59 and 60 supply steam, preferably of comparatively low pressure and of the required moisture content to the space between the sides of the casing or apron 43, and thereby produces a continuous flow of vapors outward through the sides of the casing or aprons.

The water, which, has above been referred to as flowing downward from the pipes 45, will therefore come in contact with the steam escaping through the holes in the pipes 58, 59 and 60, and will cause vaporization of the latter, which action will still further increase the saturation or water content of such steam vapors.

Ordinarily the temperature of the water so introduced to the pipe 45 is of comparatively low order, that is, little if any above atmospheric temperature, but obviously it may be raised to a higher point, if deemed advisable under certain conditions. The mixture of steam and water thus produced affords when necessary, a very wet or moist steam, and a very completely saturated vapor at low pressure. It is therefore much cooler than steam that could be introduced by allowing it to expand entirely outside of the ager. The action of this moist steam between the sides of the apron or casing is an expansive one, and therefore tends to pass through the mesh of the wire screen, until it reaches the fabric or at least reaches the vicinity of any superheated vapors which may be produced on account of the chemical and physical reactions occurring within the fabric and dyes.

If it be necessary to use a more dry or high pressure steam than that supplied through the manifolds 33, then the valves 51 may be closed and the valves 55 opened. This will allow live steam from the manifold 57 to pass into the pipes 53, 54, 58, 59 and 60. Water from the pipes may be allowed to mix with such steam if its temperature and dryness be too great for the aging required adjacent the aprons 43. If not the water may be cut off.

It will be thus appreciated that the means and method for supplying at will more or less dry vapors or very highly saturated vapors directly to the points where they are most active, enables the neutralization, absorption, and dissipation of the excess heat produced to take place very efficiently and accurately

in accordance with the amount of temperature and moisture required.

It will also be appreciated that by reason of the control of the water supply, and of the steam supply through a manipulation of the valves 48, 51 and 56, both the water and the steam can be controlled to a nicety, thereby enabling the temperature to be fixed in any desired point, that may be necessary for a particular kind of goods being treated, and this temperature may be set substantially at any point between 212 or 213° and 235 or 240° Fahrenheit, and may be maintained at such point substantially continuously during the period of run of the ager, independently of the variations in the conditions which have ordinarily existed in the commonly used agers.

The apparatus thus provided is therefore extremely flexible and capable of being manipulated at will to produce the best results. This has been determined by actual practical operation of an ager, provided with the apparatus herein described, and it has been found to be eminently superior to any other form of aging device or any process heretofore devised for that purpose.

This process and apparatus has been found to practically solve the problem of the accurate control and maintenance of definite temperatures within an ager, and has enabled results to be obtained in processes of aging both in the depth of color and economy of dyes that were never before accomplished or thought possible.

Having thus described this form of our invention, what we claim and desire to protect by Letters Patent is:

1. The process of aging fabric having thereon vat color prints or dyes, which comprises, producing by adjustment of the flow of the incoming steam and the moisture within the ager, an atmosphere of steam vapors at the necessary minimum temperature and required moisture content at successive points in the progress of the aging action, respectively, whereby there results a substantially uniform and complete reduction and absorption of the dyes upon and within the fibres of the fabric to conserve the dyes and produce maximum color values.

2. The process of aging fabric having thereon vat color prints or dyes, which comprises, producing by adjustment of the flow of the incoming steam and the moisture within the ager, an atmosphere of steam vapors at the necessary low temperatures and high moisture contents respectively at successive points in the progress of the aging action, respectively, whereby there results a substantially uniform and complete reduction and absorption of the dyes upon and within the fibres of the fabric to conserve the dyes and produce maximum color values.

3. The process of aging fabric having there-

on color prints or dyes, which comprises, producing by adjustment of the flow of the incoming steam and the moisture within the ager, an atmosphere of steam vapors at the necessary temperature and moisture content at successive points in the progress of the aging action and continuously maintaining such temperatures and moisture characteristics for a correct period of time at said points respectively,

10 whereby there results a substantially uniform and complete reduction and absorption of the dyes upon and within the fibres of the fabric to conserve the dyes and produce maximum color values.

15 4. The process of aging fabric having thereon color prints or dyes, which comprises, providing a supply of steam at a convenient temperature and pressure, producing by adjustment of the flow and moisture content

20 of the incoming steam, an atmosphere of steam vapors at the necessary low temperatures and high moisture contents at successive points respectively in the progress of the aging action, and continuously maintaining such

25 temperatures and moisture characteristics for a correct period of time at said points respectively, whereby there results a substantially uniform and complete reduction and absorption of the dyes upon and within the fibres of the fabric to conserve the dyes and produce maximum color values.

30 5. The process of aging fabric having thereon vat color prints or dyes, which comprises, producing by adjustment of the flow and moisture content of the incoming steam, an atmosphere of steam vapors at the necessary low temperatures and high moisture contents at successive points in the progress of the aging action, introducing additional moisture in

35 fluid form, with the incoming steam at points where the reactions are greater, maintaining the steam vapors throughout the process at low pressure and temperature and adjusting the steps of the process and the speed of travel

40 of the fabric through said atmosphere so that the periods of time after the initial reductions of the dyes during which the said vapors act shall correspond to and substantially dissipate the discharge of heat developed by the

45 reactions, and accommodate the time required for absorption of the reduced leuco bases by the fibres of the fabric, whereby there results a substantially uniform and complete reduction and absorption of the dyes upon and within the fibres of the fabric to conserve the dyes and produce maximum color values.

50 6. In the process of aging vat color printed or dyed fabric, the step which comprises applying vapors of a vaporable fluid and positively injecting and controlling the same

55 and the required degree of moisture at predetermined points during the treatment of the fabric to absorb and dissipate the excess heat generated adjacent said points.

60 7. In the process of aging vat color printed

or dyed fabric, the steps which comprise applying steam from an external source thereof, positively injecting and controlling the same at portions of the fabric being treated where excess heat is generated, and maintaining said steam at the desired degree of temperature and moisture, by supplying at said portions, moisture in addition to the moisture carried by the steam, to absorb and dissipate the excess heat generated adjacent such points.

75 8. In the process of aging vat color printed or dyed fabric, the step which comprises establishing a flow of steam from an external source thereof, injecting the same at points directly between adjacent runs of the fabric, and causing the same to combine with water at such points to determine the degree of moisture therein, thereby absorbing and dissipating the excess heat generated adjacent such points.

80 9. In the process of aging vat color printed or dyed fabric, the steps which comprise applying steam from an external source thereof directly between adjacent runs of fabric at points where excess heat is generated, and maintaining said steam at the desired degree of temperature and moisture to absorb and dissipate the excess heat generated at such points.

85 10. In the process of aging vat color printed or dyed fabric, the steps which comprise establishing a flow of steam from an external source thereof, applying the same directly between adjacent runs of the fabric at points where excess heat is generated, and supplying water at said points to maintain and control the temperature and degree of moisture of said steam.

90 11. In the process of aging vat color printed or dyed fabric, the steps which comprise establishing a flow of steam from an external source thereof, to cause currents thereof directly between adjacent runs of the fabric at points where excess heat is generated, maintaining said steam at the desired degree of temperature and moisture to absorb and dissipate the heat generated at such points and removing said vapors and the absorbed heat contained therein from the vicinity of the fabric by causing positive and rapid circulation of said vapors.

95 12. In the process of aging vat color printed or dyed fabric, the steps which comprise establishing a flow of steam from an external source thereof, to cause currents thereof directly between adjacent runs of the fabric at points where excess heat is generated, maintaining said steam at the desired degree of temperature and moisture by the addition of water at such points, and then causing a more active circulation of the vapors at such points than elsewhere, to dissipate said excess heat.

100 13. In the process of aging vat color

printed or dyed fabric, the steps which comprise establishing a flow of steam from an external source thereof, to cause currents thereof directly between adjacent runs of the fabric at points where excess heat is generated, maintaining said steam at the desired degree of temperature and moisture, distributing said steam evenly over the adjacent surfaces of the fabric to absorb and dissipate the heat generated at such points, and removing said vapors and the absorbed heat contained therein from the vicinity of the fabric.

14. In the process of aging vat color printed or dyed fabric, the steps which comprise establishing a flow of steam from an external source thereof, injecting the same directly between adjacent runs of the fabric at points where excess heat is generated, maintaining said steam at the desired degree of temperature and moisture, distributing said steam evenly over the adjacent surfaces of the fabric to absorb and dissipate the heat generated at such points, and removing said vapors and the absorbed heat contained therein from the vicinity of the fabric by positive circulation of said vapors.

15. In the process of aging vat color printed or aged fabric, the steps which comprise establishing a flow of steam from an external source thereof, injecting the same directly between adjacent runs of the fabric at points where excess heat is generated, maintaining said steam at the desired degree of temperature and moisture by the addition of water at such points causing an even distribution of the mixture of said steam and the water contained therein over the surfaces of the adjacent fabric, and removing said vapors and the absorbed heat contained therein from the vicinity of the fabric by causing positive circulation of said vapors.

In witness whereof we have signed this specification this 31st day of May, 1930.

45 EDWARD S. CHAPIN.
ARELI H. JACOBY.
